UNITED STATES PATENT OFFICE

146,215

DESIGN FOR A FOUNTAIN PEN

Irving Florman, New York, N. Y.

Application May 10, 1946, Serial No. 129,560

Term of patent 14 years

(Cl. D74—17)

To all whom it may concern:

Be it known that I, Irving Florman, a citizen of the United States, residing in the city of New York, county of New York, and State of New York, have invented a new, original, and ornamental Design for Fountain Pens, of which the following is a specification, reference being had to the accompanying drawing, forming a part thereof, in which

pen showing my new design, with the writing point exposed; and

Figure 2 is an elevational view of the fountain pen as turned about its axis through an angle of 90°, and having the writing point covered.

I claim as my invention:

The ornamental design for a fountain pen, substantially as shown.

IRVING FLORMAN.
